UNITED STATES PATENT OFFICE.

EDGAR E. AUSTIN, OF PORTLAND, MAINE.

CURRENCY SERIES.

1,418,611.

Specification of Letters Patent. Patented June 6, 1922.

Application filed June 4, 1921. Serial No. 475,031.

To all whom it may concern:

Be it known that I, EDGAR E. AUSTIN, a citizen of the United States, residing at Portland, county of Cumberland, State of Maine, have invented certain new and useful Improvements in Currency Series, of which the following is a specification.

This invention relates to paper currency, and particularly to a serial type of standard forms upon which bank notes, treasury notes, certificates of indebtedness and the like may be printed in various denominations.

The object of my invention is to provide a currency series in which bills of varying denomination may be not only readily distinguished from each other, but in which alteration of the denomination of any bill in the series is practically impossible.

According to my invention all bills of the series are of characteristic type or arrangement in which there are two contrastingly differentiated denominational areas, one of increasing dimension and the other of decreasing dimension as the denomination of the bills increases. The contrastingly differentiated denominational areas of varying dimension according to the bill denomination, not only prevent alteration of the bills but insure instant distinction of bill denominations. Each denominational area is of course preferably plainly marked with the particular bill denomination.

For the purposes of this application I have illustrated two characteristic specimens of my currency series.

Fig. 1 shows a currency unit of two dollar denomination, and

Fig. 2 shows a currency unit of twenty dollar denomination.

The bills or sheets constituting my currency series are all of uniform size and are each provided on one or both faces with a characteristic background design.

Such background is in two contrasting denomination areas 1 and 2 which vary in dimension according to the denomination of the bill.

As here shown, the body of the bill comprises an area 1 which is in a plurality of transversely spaced groups of broken lines with the spaces between said line groups suitably shaded and an area 2 which is in a plurality of spaced groups of light and heavy dots.

The area 1 is enclosed by a contrasting border 3' which is extended to set off one or

more spaces 3 within which the denomination of the bill may be printed. The bill denomination may also be printed within the area 2.

The several contrasting portions of the background design are shown in black and white in the drawing, but it will be understood that in practice the design is printed in one or more colors.

The area 1 increases and the area 2 decreases in dimension as the denominations of the bills increase so that bills of varying denomination may be readily distinguished from each other by the extent of the denominational areas themselves. This also prevents raising of bill denomination.

It will be understood that the areas 1 and 2 may be variously proportioned and differentiated. I also contemplate that such areas would be imprinted after the manner of the usual paper currency.

Various modifications in the design arrangement may obviously be resorted to within the limits of the appended claims.

What I therefore claim and desire to secure by Letters Patent is:

1. A currency series consisting of a plurality of sheets, each sheet having one face thereof provided throughout its entire extent with a background design common to the series, said background being subdivided across the sheet into two juxtaposed contrastingly differentiated sections constituting denominational areas adapted to indicate the denomination of the bill, and said areas varying in extent relative to one another according to the denomination of the bill.

2. A currency series consisting of a plurality of sheets of uniform size, each sheet having one face thereof provided throughout its entire extent with a characteristic background design common to the series, said background being subdivided across the sheet into two juxtaposed contrastingly differentiated sections constituting denominational areas adapted to indicate the denomination of the bill, one area increasing in extent and the other area decreasing in extent as the denomination of the bill increases.

3. A sheet adapted to be circulated as a currency medium and having one face thereof provided throughout its entire extent with a characteristic background design, said background being subdivided across the sheet into two juxtaposed contrastingly dif-

ferentiated sections constituting denominational areas adapted to indicate the denomination of the bill, and said areas bearing a definite relation to each other and to the 5 denomination of the bill.

4. A sheet adapted to be circulated as a currency medium and having one face thereof provided throughout its entire extent with a characteristic background design, 10 said background being subdivided across the sheet into two juxtaposed contrastingly dif-

ferentiated sections of different size constituting denominational areas adapted to indicate the denomination of the bill, the size of said areas bearing a definite relation to 15 the denomination of the bill.

In testimony whereof I affix my signature in presence of two witnesses.

EDGAR E. AUSTIN.

Witnesses:

ALBERT E. ANDERSON,
HENRY J. CONLEY.
